APPARATUS FOR HANDLING COILED WIRE
AND RODLester R. MacLeod, Ardsley, N. Y., assignor to
Anaconda Wire & Cable Company, New York,
N. Y., a corporation of Delaware

Application January 21, 1937, Serial No. 121,448

4 Claims. (Cl. 242—84)

My invention relates to apparatus for receiving coils of wire and rods from coiling machines and transferring them for storage or further manufacturing.

5 The invention relates more particularly to apparatus in which a rod, which is a heavy strand of metal such as copper, is fed onto a rotating member at a speed substantially equal to the peripheral speed of the member at the point 10 where the rod is fed to it. In apparatus of the above type, when a sufficient length of the wire or rod has been supplied to the rotating member to make a coil of the desired size and weight, the coil must be removed before a new coil can be 15 started. For this removal it has heretofore been necessary to lower the speed until the coiling apparatus is substantially stationary, then to remove the coil and again start the rotation. Wire for the new coil cannot be fed until the coiling 20 apparatus attains full speed. The necessity for slowing the apparatus to a stop with each coil greatly lessens the capacity of the coiling apparatus, because the average speed is greatly reduced by the gradual slowing and starting of the 25 apparatus.

My invention avoids the necessity for this periodic stopping and starting of the apparatus and provides a take-off mechanism for the completed coils which permits their removal while 30 the coiling apparatus is running at top speed and without interruption.

The various features of my invention are illustrated by way of example in the accompanying drawings, in which—

35 Fig. 1 is a vertical section of a coiling apparatus and removal for take-off and transfer mechanism embodying a preferred form of the invention; the parts being shown in the position preparatory to the transfer of a completed coil 40 from the coiling mechanism; Fig. 2 is a vertical section similar to that of Fig. 1 of the lower part of the apparatus of Fig. 1 showing the completed coil removed from the coiling mechanism and being transferred to a conveyor mechanism; and 45 Figs. 3 and 4 are detailed sectional views of parts of the mechanism of Fig. 1.

In the take-off and transfer mechanism of my invention a platform is provided in such a position that a completed coil may be dropped onto 50 it from the coiling mechanism. Immediately prior to the dropping of a coil onto this take-off mechanism the platform is brought to approximately the same rotational speed as that of the coiling mechanism. After a completed coil has 55 been dropped onto the platform the latter is then

brought to a stop while the coiling mechanism may continue its rotation and formation of a new coil without stopping or interruption. After the platform has been brought to a stop, the coil may be removed from it, as for example by a 5 suitable pusher and whereupon it may then be brought to the rotational speed of the coiling mechanism to receive a new coil.

In order to guide the coil in dropping from the coiling mechanism to the platform, a vertical 10 sliding guide is provided which in its upper position forms a substantially continuous inner guide from the coiling mechanism to the platform, which may then be lowered below the platform to permit the coil to be pushed sideways from 15 the latter.

Referring more particularly to the accompanying drawings, the invention is illustrated as applied to a coiling mechanism in which a length of wire or rod 10 is supplied through a guide tube 11, to a rotating annular member 12, having an inner wall 13, an outer wall 14, and a number of peripheral spaced radial supporting fingers 15, pivotally mounted by means of an upward extension 16 on brackets 17 on inner surface of the 25 wall 13 and extending radially outwardly through slots 17' in the wall. The inner wall 13 is supported from a vertical hollow shaft 18 by a connecting web or plate 19. The shaft 18 in turn is supported by bearing assembly 20 which includes 30 a thrust or supporting bearing, and is mounted on supporting beams 21. The assembly of shaft 18 and inner wall 13, together with the fingers 15 supported on the latter is continuously driven 35 from a drive shaft 22 through beveled gears 23 and 24. The outer wall 14 is supported by means of brackets 25 and ring 28 on supporting rollers 26, and is centered by outer rollers 27 which bear against the ring 28 so that both walls 13 and 14 rotate simultaneously and continuously. The 40 outer wall 14 may be locked to the inner wall and finger assembly by lugs 29 which are engaged by one of the fingers 15. It is to be understood that the above is merely given by way of example as a type of continuously driven coiling apparatus 45 to which my invention may be applied.

During the formation of the coil, such as the coil 30, the fingers 15 are held in the full line position of Fig. 1, by means of rollers 31 mounted by means of brackets 32 and a supporting plate 50 33 on a vertical rod 34 that is free to rotate with the inner wall 13. A piston rod 35 extending downwardly from a cylinder and piston 36 rotatably engages the upper end of the shaft 34 so that when pressure fluid is admitted to the lower 55

part of the cylinder 36 it lifts the rod 34 and with it the plate 33 and rollers 31 until the latter reach the point of pivotal axis of the upward extension 16 of the finger 15 and strikes a horizontal extension 37 of the finger 15 whereupon the rollers 31 throw the fingers 15 to the position shown in dotted lines in Fig. 1, thus permitting the coil 30 to drop downwardly.

The coil thus released from the coiling machine 10 is received on a platform 38 as indicated in the broken lines of Fig. 1. The platform 38 is preferably of annular construction and is mounted on a vertical cylindrical support 39 coaxially with the platform 38 and with the axis of rotation of the coil forming assembly 13, 14 and 15. In order to deaden the shock of the dropping of the coil 30 on the platform 38, the latter is supported on the walls 38 by means of pins 40 extending downwardly at spaced intervals from the plate 38 through an upper guide flange 41 and a lower supporting flange 42 projecting outwardly from the annular vertical wall 39, and having a shoulder 43 resting on springs 44. With this arrangement the shock of the falling coil is absorbed and deadened by the springs 44. The lower supporting flange 42 also carries a guide ring 45 which bears against and is guided by a series of spaced rollers 46 mounted in brackets 47 on a supporting plate 48.

30 The vertical annular supporting wall 39 is rotatably supported on a horizontal plate 49, mounted on a hollow vertical shaft 50. The shaft 50 is supported at its lower end in a supporting socket 51 having suitable bearings 52. In preparation to receive a completed coil 30, the supporting wall 39 and platform 38 are driven at the same speed as the annular chamber 12 by means of a motor 53 through a gear 54 which engages a gear 55 supported on brackets 56 on the wall 49.

40 After the completed coil is dropped onto the platform 38, the latter is brought to a stop by means of a brake 57 of any suitable type mounted, as shown by way of example on the motor 53.

A guide 58 is supported by means of a stem 59 for vertical movement from the interior of the wall 39 to the position shown in Fig. 1 in order to guide the falling coil 30. The guide 58 and the stem 59 rotate with the wall 39 as a unit. The guide 58 and its rod 59 are raised to the upper position by means of fluid pressure admitted through a pipe 60 into the lower end of the hollow shaft 50 into which the stem 59 extends and which acts as a cylinder with the stem 59 as the piston. A suitable flexible packing 61 is mounted on the lower end of the stem 59 to make it leak-proof with the cylinder 50. It will be understood that the guide 58 and the stem 59 are lifted by the fluid pressure preparatory to the dropping of a coil out on the platform and that as the platform 38 is brought to a stop, the guide 58 will be, or will have been, lowered to the position shown in Fig. 2 by withdrawing the fluid pressure through the pipe 60. The coil 30 may then be pushed sidewise from the platform 38.

65 Any suitable means may be provided for removing the coil from the stationary platform.

For example a pusher 62 supported by means of brackets 63 and rollers 64 may be operated by a cylinder 65 through a piston stem 66, to move from the position shown in Fig. 1 to that shown in Fig. 2. Through the action of the pusher the coil 30 is pushed sidewise over the supporting platform onto the belt 67 of an endless conveyor mechanism 68. Thereupon the pusher is withdrawn to the position shown in Fig. 1 and the guide 58 raised and the platform 38 accelerated to the speed of the annular chamber 12.

Through the above invention the coiling mechanism may be rotated continuously during the discharge of a completed coil, while permitting the coil to drop without abrupt change of speed and, therefore, it has substantially the same effect as though the coiling machine has been brought to a stop. The discharge coil may then be brought to a stop and discharged while the coiling machine rotates uninterruptedly.

What I claim is:

1. Apparatus for unloading coils from a coiling machine having a rotating coil forming member, comprising an annular platform positioned to receive a coil discharged from said member, means to rotate said platform at the speed of said member and to bring it to a stop independently of the rotation of said member, and a guide movable to said platform to and from said member to guide coils discharged from the member onto said platform.

2. Apparatus for unloading coils from a coiling machine having a rotating coil forming member, comprising an annular platform positioned to receive a coil discharged from said member, means to rotate said platform at the speed of said member and to bring it to a stop, independently of the rotation of said member, and a guide movable to said platform to and from said member to guide coils discharged from the member onto said platform, and a pusher for pushing the coils from said platform when said guide is lowered.

3. Apparatus for unloading coils from a coiling machine having a rotating coil forming member, which comprises a platform to receive a coil discharged from said member, a spring support for said platform to receive the shock of coils dropped thereon, and means to rotate said platform at the speed of rotation of said coil forming member and to bring it to a stop independently of the rotation of the latter.

4. Apparatus for unloading coils from a coiling machine having a rotating annular coil forming channel and coil supporting fingers in said channel, comprising, an annular platform positioned to receive a coil discharged from said channel, a spring support for said platform, an annular vertical wall supporting said spring supports, means to drive said annular wall and with it the platform at the same annular speed as said coil forming channel, and to bring them to a stop independently of the latter, and a guide movable vertically within said annular wall to and from said coil forming channel.

65 LESTER R. MACLEOD.
